UNITED STATES PATENT OFFICE

2,471,469

WIRE LAPING OR LIKE MACHINE

Wilfred John Lee Wildbore and James McConnochie Keenan, London, England, assignors, by mesne assignments, to International Standard Electric Corporation, New York, N. Y., a corporation of Delaware

Application November 3, 1945, Serial No. 626,563
In Great Britain September 28, 1944

Section 1, Public Law 690, August 8, 1946
Patent expires September 28, 1964

4 Claims. (Cl. 57-18)

1

This invention relates to improvements in wire lapping or like machines for covering a wire or other core with an outer covering in the form of yarn or the like.

On conventional machines of this type for applying a textile lapping to a conductor a rotating head holds concentrically with the conductor a cop of yarn and the conductor is drawn by a capstan through the hollow centre of the head. The yarn is taken from the cop to a guide on the periphery of the head and thence back on to the conductor around which it is lapped helically by the motion of rotation of the head and supply cop, combined with the longitudinal movement of the wire. In order to flatten the yarn, which would consist of a number of individual parallel filaments, into a ribbon it is customary to run the yarn round the smooth surface of a guide device, hereinafter known as the "spreader."

When a machine is used for a variety of different sizes of centre wire and a variety of different yarn sizes, a complete cover is secured by variation of the throughput speed of the wire. This means that the angle of the helix is changed and the relative position of the spreader to the guide point on the head needs to be changed. This is usually done either by allowing an adequate length of spreader blade so that the yarn may run where it will or by arranging for vertical adjustment being possible either in the position of the spreader or in the position of the guide point. The long bladed spreader is inefficient since it gives inadequate support for the centre wire and the methods of adjustment suffer from the disadvantage that adjustment is only possible when the head is stationary and the optimum adjustment can only be determined by a long and carefully handled process of trial and error.

The object of the present invention is to provide means whereby adjustment of the spreader position may be made while the machine is running, with the result that a more accurate adjustment may be obtained and the time occupied in adjustment is shorter. Experience has shown that a considerable improvement in quality results since the optimum conditions can be secured without difficulty.

According to the present invention the spreader is carried on a spindle which extends through the hollow head-driving spindle and its position is adjustable from below the rotary head whereby

2

tion applied to a known form of lapping head in which the single figure is a part sectional elevation of the spindle mechanism comprising the novel spreader adjustment.

5 The usual hollow head driving spindle is shown at 1 and inside this is mounted a second hollow spindle 2 which carries the spreader 3 at its top end. The inner spindle 2 is keyed to the main driving spindle by a key 4 in spindle 1 engaging in a keyway 5 cut in spindle 2. This permits the spindle 2 to be moved vertically with respect to 1 but not to rotate relative to it. Thus the spindle 2 and with it the spreader 3 is driven round with the lapping head.

15 Control of the vertical movement of 2 is arranged by a thrust collar 6 integral with the spindle, as shown in the drawing or brazed to the spindle (not shown in the drawing), and two thrust washer bearings 7. These bearings 20 are held in an adjustable housing 8 by a nut 9. The adjustable housing 8 is screwed into the stationary housing 10, fixed to the main frame of the machine, and fitted with a knurled head 11 and a lock nut 12. In the drawing the inner 25 assembly is shown in its uppermost position. Unscrewing the adjustable housing 8 from the fixed housing 10 by means of its knurled head 11 causes the whole inner assembly to be lowered and the spreader 3 is dropped relative to the 30 application head. Such adjustment may be made while the head and the inner spindle 2 are rotating and can be locked in any position by the nut 12.

As shown in the drawing the spreader 3 is 35 screwed into the spindle 2 and secured by a lock nut 13 so that some adjustment of the normal position of the spreader with respect to the spindle 2 may be obtained.

Although the various known parts of the machine have not been described it will be seen 40 from the drawing that by adjusting the height of the spreader the relative position of the latter to the guide point 14 on the head 15 is changed and the angle made by the yarn 16 on the wire 17 which passes up through the centre spindle 45 may be adjusted to the natural helix angle determined by the speed of rotation of the head and the speed of throughput of the centre core.

What is claimed is:

50 1. In a lapping head, a hollow-head driving spindle, a rotary head thereon, a second spindle co-axially mounted within said first spindle

for adjusting the position of said spreader from below said rotary head while the latter is rotating.

2. A lapping head as set forth in claim 1, in which said second spindle carrying said spreader and said first driving spindle have a pin and slot, respectively, thereby rotatably coupling the said two spindles and permitting relative axial movement between said spindles.

3. A lapping head as set forth in claim 1, in which a collar and thrust bearing is provided supporting the lower end of said second spindle carrying said spreader, a housing adjustably mounted in a fixed part of the machine and carrying said bearing so that an axial movement 15 of said housing with said thrust bearing effects a corresponding axial movement of said second spindle within said first driving spindle.

4. A lapping head as set forth in claim 1, in which a collar and thrust bearing is provided supporting the lower end of said second spindle carrying said spreader, a screw threaded sleeve 20

screwed within a fixed boss and provided with a knurled lead, a lock nut on said sleeve adapted to secure the latter in its adjusted position relative to said boss, said sleeve carrying said bearing so that an axial movement of said sleeve with said thrust bearing effects a corresponding axial movement of said second spindle within said first driving spindle.
